UNITED STATES PATENT OFFICE.

HENRY ALEXANDER OTTO, AUGUST MERTES, AND JOHN A. MITSCH, OF ALLEGHENY CITY, PENNSYLVANIA.

PIPE-HANGER.

SPECIFICATION forming part of Letters Patent No. 341,765, dated May 11, 1886.

Application filed October 22, 1885. Serial No. 180,613. (No model.)

To all whom it may concern:

Be it known that we, HENRY ALEXANDER OTTO, AUGUST MERTES, and JOHN A. MITSCH, citizens of the United States, residing at Allegheny City, in the county of Allegheny and State of Pennsylvania, have invented certain new and useful Improvements in Pipe-Hangers; and we do hereby declare the following to be a full, clear, and exact description of the invention, reference being had to the accompanying drawings, which form part of this specification.

Our invention has relation to pipe-hangers, and relates more particularly to that class of pipe-hangers wherein a ring, loop, or stirrup is attached to the end of a screw-threaded bolt or support, which latter is screwed into the wall, ceiling, or other place from which the pipe is to be suspended, while the loop contains and sustains the pipe.

Our invention has for its object the provision of a pipe-hanger of novel and ingenious construction, of but slight cost, and requiring but little fitting or finishing in the manufacture of the same.

Having these objects in view, our invention consists in the peculiar construction, combination, and arrangement of parts hereinafter described and claimed and illustrated in the accompanying drawings, wherein—

Figure 1 is a perspective view of our improved hanger complete. Fig. 2 is a top view, and Fig. 3 a vertical sectional view, of the same; and Fig. 4 is an elevation of the hanger ready for the reception of a pipe.

In the several figures similar letters of reference designate like parts, and A designates the screw-bolt, which forms one of the component parts of the hanger, and is formed with a square head, a' , and a screw-threaded point, a .

B designates the loop, ring, or stirrup through which the pipe passes, and by means of which it is sustained. The loop B proceeds from and is made integral with a head, C, which is formed with a vertical slot, D, ending in a square socket, d , into which fits the square head of the bolt A.

The head C and the loop B are made in two parts, the head being divided vertically at one side of the vertical slot D, and the loop being divided to one side of its center.

The piece made separate from the head and loop will be called the "tongue," and is lettered F, and it will be noted that when the said tongue is removed from the loop the latter is left open on one side, and as the upper part of the tongue forms one side of the vertical slot D and the cavity d the bolt may be detached from the head by moving it sidewise.

On each side of the vertical slot D, near its edge, are formed grooves e e , and upon the face of the tongue next to said slot is formed a square block, f , having all of its sides undercut or beveled inwardly, as seen at f' . The edges of the block f fit in and slide in the grooves e e , thus making a dovetail connection between the tongue and the head C. When the tongue is aligned with the bolt, as in Figs. 1, 2, and 3, its lower end meets the end of the loop B, and thus completes the circle of said loop, entirely surrounding the pipe laid therein. The lower end of the tongue is formed with a lug, g , and the end of the loop is formed with a notch, h , for the reception of said lug, the connection thus made serving to prevent lateral play of the tongue, and somewhat relieving the strain on the dovetail connection of the tongue and head.

Figs. 1, 2, and 3 show the loop and tongue in the position which they should occupy after the pipe has been finally adjusted in position. In Fig. 4 the hanger is illustrated as ready for the reception of the pipe. In this figure it will be observed that the tongue stands at right angles to the bolt and loop, leaving the latter open on one side for the entrance of the pipe.

To arrange the hanger in the position shown in Fig. 4, the tongue is slipped up in the direction of the bolt, and after the edges of the block f are out of the grooves e e the tongue is turned around at right angles to the bolt and loop. The top and bottom edges of the block f are now passed into the grooves e e , and the tongue remains in the position shown in Fig. 4.

The hanger complete, it will be seen, consists of but three parts—the loop, the bolt, and the removable tongue. The loop and the tongue may be readily cast in proper form, requiring but little or no fitting or finishing, and the bolt is already an article of manufacture readily attainable.

If desired, the bolt may be provided with a

slot across its head, in the manner of an ordinary wood-screw; but this will probably be found unnecessary, as the loop forms a convenient handle, by means of which the bolt 5 may be turned, the square head of the latter fitting its square socket in the head of the loop, and the bolt being therefore held rigidly therein.

Having fully described our invention, we 10 claim—

1. A pipe-hanger consisting of a loop having a head with a socket for the reception of a bolt-head, said socket being open on one side, and having the edges of said opening dovetailed or 15 grooved, and a tongue adapted to fit in and close said open side of the socket, substantially as described.

2. In a pipe-hanger, the combination, with the loop B and the head C, having a socket or 20 hole for the reception of a bolt and vertical grooves *e e*, of the tongue F, having the block *f*, whose edges fit in said grooves, substantially 25 as described.

3. In a pipe-hanger, the combination, with a loop and a head made integral therewith and 25 provided with a dovetail groove, of a tongue having a square block dovetailed on all sides and adapted to fit in said groove in two positions, substantially as described.

4. In a pipe-hanger, the combination, with 30 the loop B, open at one side, the head C, having the vertical slot D, with socket *d* and grooves *e e*, of the bolt A and the tongue F, provided with block *f*, beveled on all sides and adapted to fit in said grooves, substantially as described. 35

In testimony that we claim the foregoing we have hereunto set our hands this 17th day of October, 1885.

HENRY ALEXANDER OTTO.
AUGUST MERTES.
JNO. A. MITSCH.
